United States Patent Office.

LUKE CHAPMAN, OF COLLINSVILLE, CONNECTICUT, ASSIGNOR TO
THE COLLINS COMPANY, OF SAME PLACE.

Letters Patent No. 94,710, dated September 14, 1869.

IMPROVEMENT IN WRENCH.

The Schedule referred to in these Letters Patent and making part of the same.

To all whom it may concern:

Be it known that I, LUKE CHAPMAN, of Collinsville, in the county of Hartford, and State of Connecticut, have invented a new and useful Improvement in Wrenches; and I declare the following to be a full and exact description thereof, reference being had to the accompanying drawings, and to the letters of reference marked thereon, forming a part of this specification.

My improvement relates to that description of wrenches popularly called "monkey-wrenches."

In the drawings—

Figure 1 is a side view of my improved wrench.

Figure 2 is a sectional view of my improved wrench, the front of the wrench being toward the observer.

Like letters indicate like parts in all the figures.

From the nature of my improvement, it is only applicable, for good service, to wrenches made of cast-steel, or of wrought-iron. Malleable iron and cast-iron could be adopted, but without durability, and at great loss to manufacturer and consumer.

The letter *a* designates the head of the wrench, made of one piece, with the bar *b*, in the usual manner, which is fastened to the handle *c* by a nut at the lower end.

e is the movable jaw, sliding, as is usual, upon the bar *b*.

g is the nut, interiorly threaded and running upon the thread cut upon the front side of the wrench-bar, as seen in the drawings.

It will be observed that the lower part of the movable jaw *e* runs down upon the two flat sides of the bar, through the nut *g*, and terminates upon each side in the shoulder *e'*.

Conceding that the parts are in this position, it will be readily understood that as the nut *g* is rotated, so the movable jaw will be moved up or down, as desired.

Now to explain how the parts are got into this position. While *e* and *g* are still separate from the rest of the wrench, the slender parts of *e*, terminating in the shoulders *e'*, are pinched together and shoved through the nut *g*, and the natural spring of the parts (remembering that the material is steel or wrought-iron) will press the shoulders *e'* out against the nut. Now the movable jaw, the nut *g* being on it, is pushed on over the lower end of the bar *b*, the handle *c* is then secured on, and all the parts are then in the position shown in the drawings.

I claim, as my invention—

The movable jaw *e*, provided with the parts *e'*, in combination with the bar *b* and nut *g*, when constructed as described, for the purpose set forth.

Dated June 19, 1869.

LUKE CHAPMAN.
